Primary Examiner—Wallace R. Burke**Assistant Examiner—Melody Brown****Attorney, Agent, or Firm—Willian Brinks Hofer Gilson & Lione****[57] CLAIM**

The ornamental design for a bicycle shroud, as shown and described.

DESCRIPTION

FIG. 1 is a left, front perspective view of a bicycle shroud showing our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left, front perspective view of a bicycle shroud showing a second embodiment of our new design;

FIG. 9 is a left side elevational view FIG. 8;

FIG. 10 is a right side elevational view FIG. 8;

FIG. 11 is a front elevational view FIG. 8;

FIG. 12 is a rear elevational view FIG. 8;

FIG. 13 is a top plan view of FIG. 8; and,

FIG. 14 is a bottom plan view of FIG. 8.
